UNITED STATES PATENT OFFICE.

SYLVESTER E. AMENT, OF AURORA, ILLINOIS.

WINDMILL.

SPECIFICATION forming part of Letters Patent No. 235,333, dated December 14, 1880.

Application filed August 4, 1880. (Model.)

To all whom it may concern:

Be it known that I, SYLVESTER E. AMENT, of the city of Aurora, county of Kane, State of Illinois, have invented new and useful Improvements in Windmills, of which the following is a specification.

Some of the more salient or general features of my invention may be enumerated as follows: I use what is, or may be, termed a 10 "solid" vertical wheel and one rudder—a flexible one. The longitudinal center of the rudder is in line with the longitudinal center of the wheel-shaft when the full face of the wheel is toward the wind. The axis of the main vertical bearing of the wheel-shaft and of the rudder are all in the same vertical plane. The 15 rudder is hinged to the frame carrying the wheel-shaft, and is adapted, with the aid of other parts, to hold the full face of the wheel toward the wind, and also to present the wheel 20 at any angle to the wind, from its thin edge to its full face, when required. The hinge-bearings of the rudder vertically are sufficiently distant from each other to sustain a rudder whose authority the wheel will not dispute. The two 25 main vertical bearings are also vertically sufficiently distant from each other to sustain the apparatus advantageously. The said wheel has three motions, one in which it revolves or turns with apparatus upon main vertical axis, one in which it rotates upon its own or horizontal axis, and one in which it advances and 30 recedes a certain space by means of the sliding of the shaft upon which it is fixed. The rear end of the wheel-shaft is so connected to the forward end of the rudder that when the latter swings back the wheel and shaft slide forward, and when the rudder swings forward the wheel and shaft slide back. Neither can 35 move without the other, and which feature constitutes an important part of the self-governing principle. But one chain and one weight are used, the latter located near the ground, where it may be easily reached and regulated. 40 By means of an automatic lever, to which said chain and weight are attached, the mill is adapted to be stopped automatically by a surplus of wind or by a surplus of water, to be started again by the attendant. It is adapted, 45 also, to be stopped automatically, as aforesaid, by means of a surplus of wind or of water, and

to be started again automatically (upon the subsidence or disappearance of the said surplus of wind or of water) by means of the weight above mentioned. The lower part of 55 the piston-rod is adjustable to any desired length of stroke. The rear end of the wheel-shaft is inclosed, and has its end bearing in a socket, securing slight friction and more perfect retention of oil. The wind-surfaces of the 60 wheel are composed of narrow slats tapering from the outer end toward the center of the wheel, the rear edge of each passing a little behind the front edge of its successor, and the front edge of each passing a little forward of 65 the rear edge of its predecessor, so that to an eye on a line with the axis of the wheel-shaft the light between the peripheries of the wheel and its central circular space will be obstructed. The narrower the slats the thinner the wheel, 70 and the thinner the wheel the less resistance offered to the wind when the edge of the wheel is turned toward it. A vertical wheel presents its thin edge, not only to horizontal currents, but also to vertical and oblique currents 75 of wind. A solid wheel is simple in construction, durable in use, and noiseless in operation.

Having thus indicated to some extent the result or object of my invention, I will now proceed to give a more detailed description, 80 reference being had also to the accompanying drawings, in which—

Figure 1, Sheet 1, is a plan view. Fig. 2, Sheet 2, is a central vertical section. Fig. 3, Sheet 3, is a side elevation. Fig. 4, Sheet 1, 85 is a front view of the detached part; and Fig. 5, Sheet 4, is a side view of a prominent feature and some of its connections.

The apparatus is represented in this instance as being mounted upon a tower, A, of 90 four posts, which latter converge toward and unite at the top. The two main vertical bearings B and C are contained within the upper part of the said tower, one, B, at the top, and the other, C, some distance below the top.

The upper bearing, B, has a flange, which beneath projects over and rests upon the top of A, and above has a faced surface surrounded finally by a dishing rim, B', to retain oil, and upon which faced surface stands or rests the 100 faced surface of the shoulder D' of the main frame F D.

The lower bearing, C, when the apparatus is supported upon four posts, (but differently as to lugs and bolts when supported upon one or less than four,) has also a flange with a dish-ing rim, C', to retain oil, and four lugs. A bolt, e, formed at a right angle near its head, passes vertically through a slot in each lug, thence outward in a horizontal direction through a cleat, e', each cleat resting upon two posts, bolt running between.

A portion of the upper end of the wrought-metal pipe D is cast solid into the lower part of the main casting F, the lower part of the said pipe D being contained within the main vertical bearings B and C with sufficient looseness to allow the same to turn therein.

The shoulder D', terminating the lower end of the cast part of the main frame F D, stands or rests upon the faced surface within the dish-ing flange of the upper end of the upper bearing, B, as aforesaid.

The cast part F of the main frame F D divides at the top of the pipe D and unites again, twice near the middle and once again at the top.

The sheave S' is situated between the two middle unitings described.

Through the two horizontal bearings F' F'' in the upper part of the main frame F D is inserted the wheel-shaft G, upon the forward end of which is fixed the hub or spider G', and to which latter the arms and sections of the wind-surfaces of the wheel are attached when the parts of the wheel are applied together, but which, for obvious reasons, are not necessary to be represented in this connection. The said hub G' may be secured upon G by means of a shoulder behind it, and a set-screw inserted parallel with the axis of G, between G and G', half of the screw embedded in each. The rear end of the said wheel-shaft G is enclosed in and has its end bearing in the socket H'' of the casting H. The two screws h h, one on each side of H, enter a rectangular groove cut upon the shaft G, near the rear end thereof, and which screws thus inserted prevent the parts G and H from slipping apart.

The blanks h', f', and f'' represent oil-boxes.

Between the two horizontal bearings F' F'', and upon the wheel-shaft G, is fixed the eccentric-disk E, whose bearing upon G is of sufficient looseness to allow the latter to slip through it freely back and forth, and which, with its hub ends, fills the space between the said bearings F' F'', with the exception of only sufficient play to allow the same to turn therein.

The set-screws e e in the said hubs of E are for the purpose of taking up the wear between G and E.

The peculiar wedge I, Fig. 4, Sheet 1, is formed in this case by welding one edge of a piece of metal to one side of the shank of a bolt, and which is employed in the slot E', which latter exists in and through the disk E

from one side to the other, and through one side of the hub of the disk, as represented. Inserting the wedge from one side and putting the nut on again upon the other, the wedge is slipped down and the nut screwed up to keep it in place.

The lower edge of the wedge I sets in a groove or channel cut lengthwise in the shaft G, and which groove is of sufficient length to allow the said shaft to slide freely backward and forward the requisite distance, and is of sufficient depth to allow the said wedge I to be set in to take up the wear. The lower edge of the said wedge is made slightly wedge shape, and the groove cut to correspond, and by which means the wear, as aforesaid, may be constantly taken up.

It will be seen by the sectional view of the eccentric-disk E (shown in Fig. 2, Sheet 2,) that instead of its being cast solid it is cast hollow, which hollow space is for an oil-chamber, E'', and between which latter and the bearing in the periphery of E, at or about equal distances from each other, there are three large holes, e'' e'' e'', each filled with a plug of wood, through the pores of which oil is supplied to the bearing aforesaid in the periphery of E. When the oil-chamber E'' is to be filled a hole through one of the plugs of wood and another through the eccentric-strap may be brought in communication with each other, which may be indicated by file-marks on the outside of eccentric strap and disk. The hole should be in the plug that passes over the shaft G first, starting with the plug opposite G down. The holes e'' should be made slightly tapering, the largest ends outward.

The ends of the eccentric-straps J J are secured together by the upper ends of the outside pitman-rods, j j, collars beneath and nuts above, as represented, and to the lower ends of which latter is secured the cross-head K, collars above and nuts beneath, as represented.

The pipe L receives the collar L', which slips on at a good fit and rests upon a shoulder on L. The upper end of the pipe L is then thrust through an aperture or slot in the middle of the said cross-head K, when it takes the nut L'', which is screwed on and the upper end of the pipe spread at different points to keep the nut from working off. The said cross-head K has raised bearing-points above and below at the middle, which prevent its upper and under surfaces from touching anywhere except at the middle; and the said slot or aperture in K, through which the pipe L is inserted, is sufficiently small or shortened at the middle, and sufficiently lengthened above and below in the direction of the length of K, to prevent the head K from getting away to any considerable extent from its central bearing-points on L' and L''. But in putting the parts together the pipe L passes first through its vertical bearing M, and then through the collar L', cross-head K, &c.

The bearing M sits upon the upper end of

the pipe D and casting surrounding it, a portion thereof extending down into the pipe D a distance, as represented. It has an oil-chamber, m, surrounding the pipe L, with oil-holes 5 leading from it to L. The bearing M is strongly secured to its place by the accuracy with which it is fitted to the inside of D, and by means of the two arms m' m', one on each side, situated directly over corresponding arms m'' m'' cast upon F, and a couple of links, m''' m''', one on each side, dropped over m' m' and driven on beneath m'' m'' to hold them together.

The upper end of the chain S is connected, 15 by means of a clevis in this instance, to the web or brace of F at s, whence it is carried around the sheave S'' in the rear end of the casting H, thence through an aperture in the rear part of F and over the sheave S', and 20 thence down into the pipe L and attached to a long weight therein. But the meeting of the weight with the lower end of the chain S within the pipe L, as represented in Figs. 2 and 3, is for the purpose only of saving space. 25 In the field-machine or working device it is carried down through the pipe L and down to a certain point in the tower, and attached to a lever, to which a weight is attached, as represented in Fig. 5, Sheet 4, hereinafter described.

In the working device or field-machine the wind-surface or vane part of the rudder R is of thin matched stuff arranged vertically in a saw-kerf or incision in the longitudinal centers 35 of two bars of wood, the latter extending to the rear end of the vane part and forward to within a little distance from the hinge-arms of F. The upper bar of wood is bolted to the upper side, and the lower bar to the lower side, 40 of their respective hinge-straps R' R', and which latter extend forward of the hinge-hooks f f, turning at f f, in this instance, to the right at an angle of forty-five degrees or thereabout. The ends of the vertical pipe P, inclosed 45 between the forward ends of the said hinge-straps R' R', enter the latter a slight distance, and the bolt P', passing through the ends of R' R' and through the said pipe P, secures the parts strongly and rigidly together, securing also 50 the said hinge-straps R' R' upon the said hinge-hooks f f. The said pipe P stands in the slot H' of the casting H, the leaf or part of said casting containing said slot resting upon a collar, p, the latter fixed rigidly upon 55 P, as represented. The hinge-hooks f f should be of wrought-iron and cast solid in the hinge-arms of F.

The volute wire springs N and N' are attached, the spring N to the under side of the 60 upper, and the spring N' to the upper side of the lower, hinge-arm of F, their centers in line with the axis of the hinge-hooks f f. The outer end of each is turned into a hook, which hooks catch upon the pipe P. The inner end 65 of each should turn outward at a right angle to the plane of spring and enter F, and coil

from thence in a volute curve or spiral about the inner end of their respective hinge-hooks f f, beneath a nut and washer upon the latter to keep them in place. The said springs N 70 N' fold the wheel and rudder together when there is insufficient wind for the purpose.

When the lever attachment W X W' X' Z, Fig. 1, Sheet 1, is connected to the working parts, W and X are pivoted to the tower in 75 what may be termed the "third story" thereof, (when the mill is mounted upon a tower,) the lever W pivoted at w and the lever X at x. The rear ends of the levers W and X are connected to each other by means of the bar Z, 80 the upper end of latter being jointed to the rear end of W, and the lower end of same being jointed to the rear end of X, as represented. And, again, the lower end of what may be termed the "upper section," W', of the vertical sliding rods W' X' is jointed to the forward end of the lever W, and the upper end of what may be termed the "lower section," X', 85 of the said vertical sliding rods W' X' is jointed to the forward end of the lever X. 90 The parts W' and X' are continued in length to whatever extent is necessary, and are carried in guides—wooden ones usually—located at different points up and down in the tower, and in which they (W X) slide upward and downward. The upper end of W' is coupled to one side of the lower end of the pipe L, the latter continued in length at lower end far enough, of course, to prevent upper end of W' from coming in contact with lower end of pipe D. 100 The lower end of X' is made attachable to pump-rod or other device to be operated. The stroke of X' is lengthened or shortened as the hole x is placed at a greater or less distance from the middle of X toward Z. An unusually long stroke, for one thing, is sometimes desirable in piston of pump-cylinder of great length and small diameter, employed usually in wells constituted simply of pipe driven into ground, or dropped into hole drilled through 105 rock. The precise length of stroke desired is readily obtained. The device also permits the placing of center of tower over center of mill. 110

The sliding or automatic lever V (represented in a detached state in Fig. 1, Sheet 1, and represented in its working relations in Fig. 5, Sheet 4, particularly to G and R) is pivoted to the tower, in a field-machine, in what may be termed the "second story" thereof, when the mill is mounted upon a tower.

The standard or frame Q Q Q is simply for the purpose of sustaining V and G and R in their working relations.

The shaft G is represented in Fig. 5 only in its capacity to move endwise.

The chain S (represented by a chain in Fig. 1, and by a cord in Fig. 5) will still be designated as the chain S.

Sheaves are employed in the field-machine to relieve the friction at the angles turned by 130 rope or chain, but which in Fig. 5 are dispensed with. The said lever V is pivoted at

v upon a cylindrical arm, in this instance Q', one end of which latter is secured to the frame Q. The said lever V is kept in place upon the said arm Q' by a staple-like device, Q'', the 5 legs of which pass obliquely through Q', one each side of V, and the upper or horizontal part of which serves the purpose of a stop to V, limiting the upward movement of the outer end of latter. The lower end of the chain S 10 is attached to the said lever V at v'.

The holes v'' v'', one at each end of V, are to attach a rope to, said rope to extend down to attendant's hand to operate lever in part.

The rod V' is crooked near each end at a 15 right angle, or nearly so, and the ends passed up through the lever V and secured by a nut each, as represented.

The link to which the weight V'' is attached is adapted to slide back and forth upon the rod 20 V' from one end or corner to the other, and to be retained at the ends, especially the outer end, when required.

The sub-lever Y is secured to the upper side of the outer end of the lever V upon the outer 25 end of the rod V', near its middle, and at its forward end upon a pin or dowel fixed rigidly in V, as represented.

One end of the rope Y' is attached to the outer end of the sub-lever Y, the other end carried upward, thence in a horizontal direction through the supports or guides q q, thence 30 down to and attached to the thin weight Y'', representing the bucket, which latter, in the field-machine, is suspended within the well 35 and adapted to be filled by surplus of water through pipe leading from tank at high-water mark.

It will be perceived that the mill is turned from the wind when the outer end of the lever 40 V is elevated, and is turned toward the wind when the outer end of V is lowered. Now the outer end of V may be elevated by attendant, by wind, or by water, and may be lowered by attendant or by weight.

45 It will be seen that the weight V'' performs two offices. It is not only a weight to the lever V, but is also a weight to the sub-lever Y; but the leverage it has upon the chain S is very different from what it has upon the rope 50 Y'. Its leverage upon the latter is intended to be only sufficient to a little more than balance the weight and friction of the bucket and rope Y'' Y', and thereby require but a small amount of water in the bucket to elevate the

55 outer end of the sub-lever Y, while it may require an additional amount sufficient to fill a capacious bucket to elevate the outer end of V. It depends upon the weight of V'' and the force at the time of the wind. When suf-

60 ficient water has run into the bucket to overcome the gravity of the lever V with weight attached the outer end of V rises from the lowest point to which it is permitted by the chain S to descend to the highest point it 65 is permitted by the stop Q'' to be elevated. The first thing elevated, however, is the outer

end of the sub-lever Y, which movement of latter elevates the outer end of the rod V' into contact (at a certain remote period, subsequent to which juncture V also begins to rise) 70 with the underside of V, between the two pins v''' v''', with the upper end of the link V'' behind them, in which relative position the parts remain during the ascent, stoppage, and descent of the outer end of V. When, during 75 said stoppage, sufficient water has leaked out of small hole provided in bottom of bucket the weight V'' draws the outer end of V down again.

If during said stoppage the outer end of V comes to be sustained by wind through 80 medium of chain S, and continues to be for a sufficient time, the weight V'' will eventually be released and slide to the forward end, where it remains until outer end of V is lowered by attendant.

If the outer end of the lever V is 85 elevated by wind instead of by water, or by attendant instead of by water, or by wind, the weight V'' is permitted to slide to the forward end and there remains until the outer end of V is lowered again by attendant. By 90 tying the outer end of Y down with small piece of rope to V the weight V'' is allowed to slide to the forward end, not only when the outer end of V is elevated by wind or by attendant, but also when it is elevated by water, 95 and at which point the said weight remains until the outer end of V is lowered by attendant, when it slides back to the rear or outer end again. By tying, or by some means securing, the weight V'' at the outer end of V 100 the weight V'' is retained at the outer end during the ascent, stoppage, and descent of the outer end of V, when the latter is elevated by water, by wind, or by attendant. With the rope Y' detached the outer end of the lever 105 V may be elevated by wind or by attendant, and lowered by attendant or by weight, as before.

When the mill is permitted to turn from the wind, and when outer end of V for that purpose has been elevated by water, the outer end of V, with weight V'', remains in said elevated position, and mill remains out of wind until enough water has leaked out of small hole provided in bottom of bucket to enable gravity 110 of weight V'' to automatically lower outer end of V, and thereby turn mill toward wind again to fill again the tank, and then again the bucket, and so on. But when it is desired that the mill may be thrown out of wind by water, 115 to remain out until thrown into wind again by attendant, the outer end of the sub-lever Y may be tied down to the lever V, whereby the weight V'' will be allowed to slide to the forward end of its sliding rod V', which disposition of parts retains outer end of V at its elevation, and mill remains out of wind until drawn into wind again by attendant, as aforesaid.

The weight V'' should be of sufficient heft 120 to hold the mill in as strong wind as it is desired to run in. When the wind becomes

stronger than that the outer end of the lever V is elevated, and the weight V'' (with Y tied down, or with Y' detached) slides to the opposite end and to the opposite side of the pivot 5 v, thereby relieving the chain S entirely of any of the gravity of the lever V or parts belonging thereto, and which stops the mill, to be started only again by the attendant. If, however, it is desired that the mill be brought 10 automatically into wind again each time soon as its surplus force has subsided, it may be done by tying or otherwise securing the weight V'' at the outer end of its sliding rod V'. The weight, however, can be made heavy 15 enough to hold the mill in any wind it might be desired to run—or, perhaps, might better say, stop in—for safety of well-covering, pump-fixtures, &c.; but the greatest point of utility exists in the fact that the mill is safe from 20 being whipped out of wind by the wind and whipped into wind again by the weight alternately throughout an entire storm of gusts or heavy blows alternated by short recesses of calms; but, on the contrary, the first force of 25 wind that occurs that is strong enough to throw the mill out of wind places it out of danger, especially so far as whipping is concerned. It obviates the difficulty of whipping entirely.

30 The inertia of the parts and the momentum of their movements when overcome suddenly, and not only suddenly but rapidly in succession, do not, to say the very least, do the machine any good.

35 When the wind, through the medium of the shaft G, chain S, &c., becomes strong enough to overcome or elevate the weight V'' below, the wheel and shaft G' G are carried back until the hub of G' strikes the forward end of the 40 bearing F', which movement, by means of the connection between the rear end of the shaft G and the forward part of the rudder R, (hereinbefore described,) throws the rudder R around parallel, or nearly so, to the disk of 45 the wheel, as indicated by the dotted outline, Fig. 1, Sheet 1, in which relative position of parts the wind turns the apparatus around on main vertical axis until the edge of the wheel is presented to the wind. When the force of 50 the wind subsides sufficiently to give to said weight the preponderance of government (assuming that the said weight is secured for the time being at the outer end of V') the weight, by means of the chain S, attached as described, 55 carries the wheel and shaft forward again until the casting H comes in contact with the rear end of the bearing F'', which brings the rudder R, by means of the connection between it and the shaft G, described, around back 60 again into line, or nearly so, with the shaft G, and at right angles, or nearly so, to the disk of the wheel G', in which relative position of parts the wind turns the apparatus around on main vertical bearings or axis aforesaid in the 65 tower until the full face of the wheel is pre-

sented to the wind. Both operations, however, are in reality being performed at the same time—that is, the turning of the rudder upon its hinge and the entire apparatus upon its main vertical bearing, whether to or from 70 the wind.

I claim as my invention—

1. The combination of the main vertical bearings B and C, chambers B' and C', pipe D, shoulder D', and casting F, substantially as 75 and for the purpose hereinbefore set forth.

2. The combination of the bearing M, chamber m, arms m' m', arms m'' m'', links m''' m''', pipe L, pipe D, and casting F, substantially 80 as and for the purpose hereinbefore set forth.

3. The combination of the cross-head K, pipe L, collar L', and nut L'', substantially 85 as and for the purpose hereinbefore set forth.

4. The combination of the wedge I, disk E, and shaft G, substantially as and for the purpose hereinbefore set forth.

5. The combination of the wedge I, bolt I', disk E, shaft G, and screws e e, substantially 85 as and for the purpose hereinbefore set forth.

6. The combination of a wind-wheel, G', 90 wind-wheel shaft G, disk E, chamber E'', and eccentric-straps J J, substantially as and for the purpose hereinbefore set forth.

7. The combination of a wind-wheel, G', wind-wheel shaft G, disk E, chamber E'', 95 one or more apertures, e'', and eccentric-straps J J, substantially as and for the purpose hereinbefore set forth.

8. The combination of the chain S, sheaves S' S'', casting H, shaft G, and frame F D, substantially as and for the purpose hereinbefore 100 set forth.

9. The combination of the casting H, screws h h, sheave S'', and shaft G, substantially as and for the purpose hereinbefore set forth.

10. The combination of a wind-wheel, G', wind-wheel shaft G, socket H'', chain S, one or more sheaves S' S'', weight V'', frame F D, and flexible rudder R, substantially as and for the purpose hereinbefore set forth.

11. The combination of the rudder R, hinge-straps R' R', pipe P, and bolt P', substantially as and for the purpose hereinbefore set forth.

12. The combination of the rudder R, straps R' R', casting H, slot H', bearing P, sheaves S' S'', chain S, wheel and shaft G' G, and frame F D, substantially as and for the purpose hereinbefore set forth.

13. The volute springs N N', in combination with the frame F D, rudder R, and sliding 120 wheel and shaft G' G, substantially as and for the purpose hereinbefore set forth.

14. The combination of the two levers W X, connecting-bar Z, and sections W' X' of the vertical sliding rods W' X', substantially 125 as and for the purpose hereinbefore set forth.

15. The combination of the lever V, rod V', chain S, and weight V'', substantially as and for the purpose hereinbefore set forth.

16. The combination of the lever V, rod V', 130

chain S, weight V'', and sub-lever Y, substantially as and for the purpose hereinbefore set forth.

17. The combination of the lever V, rod V', chain S, weight V'', sub-lever Y, stop Q'', and holes v v' v'' v'' y, substantially as and for the purpose hereinbefore set forth.

18. A lever, V, weight V'', chain S, and sliding rod V', bucket Y'', rope Y', and sub-lever Y, by means of which the mill may be stopped automatically by a surplus of wind or by a surplus of water, to be started again by attendant or by weight, substantially as and for the purpose hereinbefore set forth.

19. A lever, V, weight V'', chain S, and slid-

ing rod V', through means of which the mill may be stopped automatically by a surplus of wind, to be started again by the attendant, substantially as and for the purpose hereinbefore set forth.

20

20. The combination of the main vertical bearings B and C, frame F D, advancing and receding solid wheel G', and flexible rudder R, substantially as and for the purpose hereinbefore set forth.

SYLVESTER E. AMENT.
